United States Patent

Des. 240,318
Patented June 22, 1976

240,318

CANDLE HOLDER

Mary Sovago, 1806 1st Ave., New York, N.Y. 10026

Filed Sept. 23, 1974, Ser. No. 508,458

Term of patent 14 years

Int. Cl. D26—01

U.S. Cl. D48—2

FIG. 1

FIG. 2

FIG. 3

FIG. 1 is a front perspective view of a candle holder embodying my new design;

FIG. 2 is a top plan view of said holder on a reduced scale; and

FIG. 3 is a rear view thereof on a reduced scale.

The candle is shown in broken lines in FIGS. 1, 2 and 3 for illustrative purposes only.

I claim:

The ornamental design for a candle holder, substantially as shown and described.
